Filed June 21, 1965, Ser. No. 465,524
4 Claims. (Cl. 112—227)

ABSTRACT OF THE DISCLOSURE

A needle guide for a curved needle sewing machine in which the needle is guided in a curved guideway formed in a hard insert bonded to a ferrous body of the guide.

The present invention relates generally to improvements in needle guides for curved needle sewing machines and more particularly to such needle guides in which superior wear characteristics are obtained by a needle receiving passage formed in an insert of extremely hard wear resistant material such as a cemented carbide.

In shoe inseam sewing machines such as that disclosed in Patent No. 3,088,426, issued May 7, 1963, upon application of Lloyd G. Miller and in outsole sewing machines such as that disclosed in application for United States Letters Patent Serial No. 422,853 filed Dec. 31, 1964 in the names of Joseph R. Ioannilli, Mieth Maeser and Kenneth H. Rauschke, curved needles are employed for penetrating resistive shoe parts to form stitches. In such machines the needle is supported against deflection by a needle guide which includes a curved passage formed to provide a sliding fit for the needle. Because of elastic deformation of the needle in penetrating the work piece and the heat of friction generated in modern high sewing speeds, such conventional needle guides wear rapidly and must be discarded after a short period of use because the passage is enlarged by wear and affords insufficient reinforcement or stiffening to the needle. It has been estimated that in inseam sewing machines according to the above Miller patent operated at high speed, the conventional needle guide must be replaced after 20 to 25 hours of operation. Such frequent replacement is both costly and time consuming.

It is accordingly an object of the present invention to improve the durability of needle guide for curved needles and of similar articles subjected to severe wear.

Another object of the invention is to provide a method and apparatus for forming arcuate passages accurately in extremely hard materials.

According to a feature of the invention the needle guiding passage or guideway is formed in an insert of cemented carbide. Although an insert of hardened high speed steel or of various compositions of cemented carbide may be fixed in position in the guide by silver soldering for example, it has been found that adequate accuracy of location and bond strength of the insert to the body of the guide as well as greater economy of manufacture is obtained by casting the insert as a part of an investment steel casting for example during the molding process. In order to resist the high pouring temperature of the steel it has been found that the heat resistance of chromium carbide bonded with nickel is sufficient so that the mechanical properties of the insert are not impaired. The insert is imperforate and the curved passage is formed by electrical discharge machining or EDM.

The foregoing objects and features and numerous advantages of the invention will be more fully appreciated from the following detailed description of an illustrative embodiment taken in connection with the accompanying drawings in which:

2

FIG. 1 is a fragmentary view in right side elevation of a shoe inseam sewing machine including a curved needle supported by a needle guide according to the present invention;

5 FIG. 2 is a fragmentary view in side elevation and partially in section showing the apparatus for forming a curved passage in a needle guide;

10 FIG. 3 is a view in front elevation of the apparatus depicted in FIG. 2;

15 FIG. 4 is a fragmentary view in front elevation partly in section and on an enlarged scale showing the curved passage in the process of being formed in a needle guide; and

20 FIG. 5 is a fragmentary view on an enlarged scale of a portion of a needle guide shown being completed in a subsequent operation.

25 Turning now to the drawings, there is illustrated in FIG. 1 a view of instrumentalities surrounding the sewing point of a shoe inseam sewing machine such as that disclosed in the above identified Miller application. The machine is employed for inserting a seam 10 which joins together an

30 upstanding rib 12 on an insole 14, the margin of an upper 16 and a welt 18 while the shoe parts are supported on a last 19. The machine includes a curved hook needle 20, which is supported against deflection by a needle guide 22.

35 In addition, the machine also includes normal instrumentalities of inseam sewing machines as well as an awl 24, a channel guide 26, a thread finger 28, a looper 30, and a welt guide 32. The various parts of the machine 40 already enumerated are operated in a conventional manner and serve merely to improve the understanding of the invention which relates to the needle guide 22. During normal sewing operations the needle 20 is oscillated at high speeds with respect to the needle guide 22 including a pair of spaced apart wear resistant inserts 34 in which a curved passage 36 is formed to provide a 45 sliding fit for the needle 20.

40 The needle guide 22 shown in FIG. 1 is one in which two inserts 34 are employed with a slot 37 between the

45 two inserts to provide an additional edge for scraping off wax and other material which adhere to the needle from its contact with the thread. In the other views there is shown an alternative needle guide construction including a body 38 in which is secured a single wear resistant insert 40 having a length approximately equal to the distance

50 between the exterior end faces of the inserts 34. In either case whether the single or double insert construction is involved the first step in the manufacturing of the needle guide is the production of a needle guide blank preferably by precision casting. In the casting step, an insert of sintered chromium carbide bonded with nickel such as Carboloy grade No. 608 manufactured by the General Electric Co., is positioned in the mold in much the same manner as a core would be placed to form an aperture in the

55 casting. The metal solidifies and secures the insert in position for conventional machining operations, which include the finishing to size of a mounting hole 42 to be fitted upon a needle stud 44 about whose axis the needle 20 is oscillated as seen in FIG. 1. After the conventional machining operations have been completed electrical discharge machining or EDM is employed for forming a curved passage 46 concentric with a mounting hole 47 in the needle

60 guide employing a single insert 40 or alternatively concentric with the hole 42 in the needle guide employing the spaced apart inserts 34. The use of such machines for forming straight holes in extremely hard work pieces is already known. Methods of forming curved holes in relatively soft materials using slim shanked rotary cutting tools are also well known. The shank of the cutting tool for curved holes in soft material limits the effective depth of the hole which may be machined before the curved wall of the hole interferes with the rotation of the shank. In

such curved hole machining the maximum attainable hole depth therefore is a function of hole diameter, radius of curvature and shank diameter even though the length may be doubled by machining from both ends. In the practice of the present invention not only can much harder materials be machined but also the length of the curved hole is unlimited for practical purposes. It is accordingly possible to obtain far superior durability because of harder materials as well as greater length of bearing in curved guideways.

The formation of the curved passage 46 is illustrated in FIGS. 2-4 inclusive in conjunction with a fragmentarily illustrated commercial EDM apparatus such as that manufactured by the Elox Corporation of Troy, Michigan. Various features of the machine are disclosed in United States Letters Patent including Nos. 2,415,690 in the name of A. A. Hilfeler and 2,996,638 and 3,062,192 in the name of R. S. Webb. In general, the EDM process is carried out by successive high intensity electrical discharge across a gap 48 as seen in FIG. 4. The Webb patents pertain to devices for accurately positioning an electrode carrying piston to maintain optimum spacial relationship between the electrode and the work piece by advancing the electrode along a straight line path in EDM apparatus.

In the present drawings the piston of the machine is designated by reference character 50 and in accordance with the usual practice has a straight line operating motion downwardly toward and upwardly away from a tank 52. Contained in the tank 52 is a quantity of coolant-electrolyte 54 in which the work piece is submerged. The conventional EDM apparatus includes a servo-system responsive to arc striking potential or to average current for maintaining the piston 50 constantly positioned so as to provide an optimum gap between an electrode fixedly supported on the piston 50 and the work piece submerged in the coolant-electrolyte 54.

In FIG. 2 conventional electrical sensing apparatus for positioning the electrode and a power supply to provide the necessary current for the EDM operation are designated merely as a block 56 having a positive electrical connection to a collar 58 and a negative connection grounded at 60. It will be seen from FIG. 3 that the piston 50 is also grounded at 62.

The collar 58 is part of a fixture which together with the needle guide blank 38 is mounted in the tank 52 and submerged in the body of coolant-electrolyte 54. The fixture which is electrically grounded at 64 includes an electrically conductive base 66 on which is mounted a stud 68 having an outer threaded end bearing a clamping knob 70. The stud 68 and the knob 70 are metallic and in contact with the base 66 and consequently also at ground potential. There is interposed between the collar 58 and stud 68 electrical insulation comprising a headed bushing 72 and a washer 74 to isolate the collar and the blank 38 electrically from the grounded parts already described and also from an electrode 76 which is also maintained at ground potential so that the full potential of the power supply 56 is developed across the gap 48. The electrode 76 is a curved tube including an interior passage 78 through which electrolyte-coolant is pumped continuously from a flexible tube 80 connected to the end of the electrode most remote from the blank 38. Between the electrode 76 and the piston 50 there are connections to translate the straight line motion of the piston into a pivotal motion of the end of the electrode about the axis of the stud 68. These connections include a rod 82 retained in a collet at the lower end of the piston 50. The electrode 76 is maintained on a sector 84 by a clamp plate 86 and the rod 82 is connected to the sector by a link 88 pivoted to the rod and link at 90 and 92 respectively. As a result of the connections already described, whenever the piston 50 in response to a high arc striking voltage descends toward the tank 52, the descending motion of the piston is translated into a counterclockwise motion of the electrode 76 thereby narrowing the gap 48. A rise of the piston 50 is

similarly translated into a clockwise motion of the electrode 76 and consequent widening of the gap 48.

The blank 38 is retained against turning about the axis of the stud 68 by a pair of fingers 94 and 96 placed ahead and behind the insert 40 respectively. The electrode 76 may be employed for initially machining its own arcuate guideway 98 in the finger 94 merely by insulating the base 66 from ground and connecting it to the positive terminal of the power supply 56 thus applying the electrical discharge machining potential across a gap between the electrode and the finger 94. In order to insulate the ear 94, which with the electrode 76 during subsequent machining operations is at ground potential, a slotted insulator 100 is retained by an undercut recess in the finger 94 and its outer surface 102 receives the end surface of the insert 40. A clearance passage 104 for the electrode 76 is formed in the insulator 100. Similarly the finger 96 is provided with an insulator 106 and formed with a clearance passage 108. The insulator 106 which also has a clearance passage 110 contacts the insert 40 and thus maintains the insert insulated from the base 66.

It is thus seen that the electrode 76 is directed by the accurately formed guideway 98 and that as the right end of the electrode as seen in FIGURE 4 approaches the left end of the insert 40 in an imperforate insert, the sensing apparatus of the machine continues to advance the electrode toward the insert 40 until the proper gap 48 is established. Successive electrical discharges of the machine cause erosion of the insert in the path of the electrode. As the erosion of the workpiece continues the electrode 76 is also eroded and the required pivotal motion of the carrier 84 to maintain optimum width of the gap 48 is continuously provided by vertical self adjustment of the piston 50. Both the work piece and the electrode are cooled and flushed by coolant-electrolyte introduced through the passage 78, and the electrolyte in the gap 48 also regulates in a predictable manner the current flow across the gap.

After the guideway 46 has been completely formed by electrical discharge machining, a further operation is desirable to complete the needle guide particularly when the guideway is formed in an extremely hard material such as a cemented carbine. This operation depicted in FIG. 5 consists of forming a small radius 112 at each end of the guideway 46 so as to reduce the possibility of the carbine to dig in and thus gouge the softer material of the needle 20 thereby reducing the useful life of the needle. The radius 112 may conveniently be formed by manually holding the end of the guideway 46 against a formed rotating diamond wheel 114.

In the appended claims, the article is defined in terms of hard materials. Numerous materials are useful in carrying out the present invention and the term hard should be interpreted as characteristic not only of materials which resist penetration under load but also of materials which have the wear characteristic and heat resistance at least equivalent to those hardened tool steels. Such materials are characterized by difficulty of machining by conventional apparatus comprising sharp edge cutting tools. In some cases particularly in alloys of cobalt, and chromium such as some Stellites, the hardness may be as low as 50 Rockwell C but such materials defy practical machining by means of edged cutting tools. The term hard material is therefore intended to include a broad range of ferrous and nonferrous materials which are difficult to machine but provide improved wear characteristics.

Having thus disclosed our invention what is claimed as new and desired to secure by Letters Patent of the United States is:

1. A needle guide for reinforcing a curved needle comprising a ferrous body, a hard insert bonded to the ferrous body and having a pair of exposed outer end faces and a curved guideway extending between the end faces and contained entirely within the insert.

2. A needle guide according to claim 1 in which the insert consists of cemented chromium carbide.

75

3. A needle according to claim 2 in which the insert is bonded directly to the ferrous body.

4. A needle guide for reinforcing a curved needle comprising a ferrous body, a hardened insert bonded to the ferrous body and having a pair of exposed outer end faces and a curved guideway extending between the end faces, contained entirely within the insert and formed with a

radius at the intersection of the guideway with each end face.
